2 SHEETS—SHEET 2.

UNITED STATES PATENT OFFICE.

FRANCIS T. JOHNSON, OF CHICAGO, ILLINOIS.

MECHANICAL MOVEMENT.

1,200,619.

Specification of Letters Patent   Patented Oct. 10, 1916.

Application filed April 27, 1914. Serial No. 834,575.

To all whom it may concern:

Be it known that I, FRANCIS T. JOHNSON, a citizen of the United States, residing at Chicago, in the county of Cook and State of Illinois, have invented a certain new and useful Improvement in Mechanical Movements, of which the following is a specification.

My invention relates to improvements in washing machines and is illustrated diagrammatically in one form in the accompanying drawings, wherein—

Figure 1 is an end elevation with parts in section and parts cut away; Fig. 2 is a section along line 2—2 of Fig. 1; and Fig. 3 is a plan detail of the clutch mechanism.

Like parts are referred to by like letters throughout the several figures.

A is a substantially cylindrical washing machine tub having at its upper end a recessed part A¹.

A² is the door of the tub held against the wall at the bottom of the recessed part A¹ by the cross-piece A³ which may be turned 25 to underlie the wall of the tub and be tightened on it by the handscrew A⁴.

A⁵ is the overflow from the tub and A⁶ the supply pipe.

A⁷ is a solid cleat to guide the clothes in 30 the tub attached to the side wall of the tub at either end and corrugated at A⁸ and provided with a comparatively narrow clearance, in actual practice about one-sixteenth of an inch in width, as at A⁹ above the bottom wall of the tub. The tub is sup-

ported on one side by a spindle A¹⁰ in a bearing A¹¹ on the end frame A¹² and is pinned on the other side to a shaft B which shaft is rotatably mounted in the bearings

40 B¹, B² on the frame B³. The bearing B¹ is carried in a box member B⁴ which is supported from the frame B³ and together with the frame forms a housing for the driving mechanism, which mechanism I will now

45 describe.

C is a drive shaft carrying a drive pulley C¹ driven by a belt C² from any suitable source of power. It is rotatably mounted in the bearings C³, C⁴ and carries a pinion 50 C⁵ in mesh with the spur gear C⁶. This spur gear C⁶ is rotatably mounted on the pin C⁷ carried by the frame B³. It is in mesh with a further spur gear C⁸ similarly supported on the frame B³. Thus these two spur gears 55 rotate in opposite directions.

D, D¹ are pins projecting outwardly from the spur gears C⁶, C⁸. Rotatably mounted on them are bearing sleeves D² upon which are mounted, held in position by the set screws D³, the spring carrying sleeves D⁴. 60 These spring carrying sleeves have hollow lugs D⁵ downwardly depending therefrom, and slidably in these lugs are piston rods or plungers D⁶ supported by the springs D⁷. Attached to the end of these rods is a chain 65 D⁸, and this chain passes over a sprocket drum D⁹ rotatably mounted on the shaft B.

E is a clutch ring keyed to the shaft B carrying a clutch arm E¹ pivotally mounted thereon.

E² is a clutch slot in the drum D⁹.

E³, E⁴ are curved clutch arm operating fingers mounted on a carriage E⁵ slidably on the guides E⁶.

E⁷ is a link to move the carriage along the 75 guides, and E⁸ is a lever arm pinned to the control rod E⁹ whereby the carriage and link may be moved by means of the hand wheel E¹⁰. The rod E⁹ is free to slide in the bearings E¹¹, E¹² and is provided with a pin 80 E¹³ in opposition to a pin E¹⁴ on the bearing E¹¹ so that, when in the position shown in Fig. 2 the clutch is locked in the out position by lifting up the band wheel E¹⁰ and then rotating it to bring the pin E¹³ upon 85 the other side of the pin E¹⁴, the clutch may be thrown in.

F are brackets supported on the frame members A¹², B³ provided for holding a wringer.

F¹ is a sprocket chain leading up to the wringer not shown and adapted to drive it. F² is a sprocket for driving this chain. This sprocket is mounted on a shaft F³ in a bracket or yoke F⁴ which yoke is pivotally 95 mounted on the shaft F⁵ and provided with controlling handle wheels F⁶. On the shaft F³ is a pinion F⁷ in the same plane as the spur gears C⁶, C⁸. It will be noted that the spur gear C⁸ moves in a clockwise 100 direction and the spur gear C⁶ in a counter-clockwise direction, so that when the hand wheels F⁶ are manipulated to bring the pinion F⁷ in mesh with the spur gear C⁸ the tendency is to make that spur gear move 105 toward the right, thus effectually locking it in position. When it is in mesh with C⁶ the reverse is the case, so no locking means are needed to hold the spur gear and the pinion in mesh.

110

The driving of my tub, that is to say the oscillatory rotation, is effected by a reciprocating movement of the chain D^s . Assuming that the parts are in the position shown in Fig. 1, the end of the chain at D will come down toward the tub, the end at D^1 will be carried up away from the tub, and the tub will then be rotated in a clockwise direction. As the rotation of the gears continues, however, the part D will commence to recede from the tub and the part D^1 will approach it, and the reciprocation of the tub will be reversed. The springs at the end of the chain give a flexible drive. The tub thus rotates or oscillates back and forth as long as the chain reciprocates. It will be obvious that any suitable velocity ratio between the tub and chain may be provided, so that if a slight movement of the tub is desired a large sprocket drum will be used and if a large movement of the tub is desired a small sprocket drum will be used. I have shown a device in which my tub rotates approximately through an arc of not more than 180° , but it might rotate through 360° or less, depending entirely upon the relative sizes of the interacting parts.

I have used the term "flexible band and wheel" as applied to the chain and sprocket, as it is obvious that mechanical parts might be used other than the chain and sprocket shown. The same is true of the term "crank pin." The crank pin does not need to be driven necessarily by gears but might be driven in other ways. They do not need to be in the same plane. They might be one in front of the other. A large number of different arrangements might be used without departing from the spirit of my invention wherein we still would have the flexible band which reciprocates and causes oscillation of the driven part.

I claim:

1. A driving mechanism comprising a rotatably mounted sprocket, a chain in mesh with and riding upon said sprocket, a plurality of gears, means for rotating them in opposite directions and means mounted on said gears to support the ends of the chain to reciprocate the chain and oscillate the sprocket.

2. A mechanical movement comprising a sprocket, a chain in mesh with and riding over said sprocket, a pair of gears, means for rotating them in opposite directions at the same velocity, the two ends of the chain being attached one to each of the gears at points separated by an angle of 180° .

3. A driving mechanism for an oscillating body comprising a pair of gears of equal diameter in mesh one with the other, means for rotating them, crank pins projecting from the surfaces thereof at equal distances from the centers of rotation, said pins being separated by an angle of 180° , a loose belt

attached at its ends to each of said pins and a driven member over which said belt travels.

4. A mechanical movement comprising a pair of crank pins separated by an angle of 180° , means for rotating these crank pins in opposite directions at a fixed angular velocity, a flexible band attached at each end to one of said pins and a wheel driven by the reciprocation of the flexible band. 75

5. A mechanical movement comprising a pair of rotating crank pins, means for rotating them at a common angular velocity, said pins being separated one from the other by an angle of 180° , a flexible band having its two ends attached one to each of said pins, an oscillatable wheel over which said band travels in driving relation thereto, and a yielding connection between said pins and said band. 80

6. A mechanical movement comprising a pair of crank pins separated by an angle of 180° , means for rotating these crank pins in opposite directions at a fixed angular velocity, a flexible band attached at each end to one of said pins, a wheel driven by the reciprocation of the flexible band and a yielding connection between said pins and said band. 85

7. A mechanical movement comprising a pair of rotating crank pins, means for rotating them at a common angular velocity, said pins being separated one from the other by an angle of 180° , an extensible flexible band having its two ends attached one to each of said pins, and an oscillatable wheel over which said band travels in driving relation thereto. 95

8. A mechanical movement comprising a pair of crank pins separated by an angle of 180° , means for rotating these crank pins in opposite directions at a fixed angular velocity, an extensible flexible band attached at each end to one of said pins and a wheel driven by the reciprocation of the flexible band. 105

9. A driving mechanism comprising a rotatably mounted member, a flexible band in engagement with the periphery thereof, a pair of gears and means for rotating them in opposite directions, the ends of said flexible band being attached one to each of said gears. 115

10. A driving mechanism comprising a rotatably mounted member, a flexible band in engagement with the periphery thereof, a pair of gears and means for rotating them in opposite directions, the ends of said flexible band being attached one to each of said gears and an elastic connection between the ends of the band and the gears. 120

11. A driving mechanism comprising a rotatably mounted member, a flexible band in peripheral engagement therewith, a pair of cranks and means for rotating them the ends 130

of said band being mounted one to each of said cranks and a yieldable connection between the cranks and the ends of the band.

12. A driving mechanism comprising a rotatably mounted member, a flexible band in peripheral engagement therewith, a pair of cranks, and means for rotating them in opposite directions, the ends of said band being mounted one on each of said cranks.

13. A driving mechanism comprising a rotatably mounted member, a flexible band in peripheral engagement therewith, a pair of cranks, means for rotating them in opposite directions, the ends of said band being mounted one on each of said cranks, and a flexible connection between the cranks and the ends of the band.

14. A driving mechanism comprising a ro-

tatably mounted member, a flexible band in peripheral engagement therewith, and rotary means for drawing first one end of said band and then the other away from the center of rotation of the rotatably mounted member to give it a reversing rotary movement, said means comprising a pair of cranks, means for rotating them, and gears upon which said cranks are mounted in mesh one with the other.

In testimony whereof, I affix my signature in the presence of two witnesses this 15th day of April, 1914.

FRANCIS T. JOHNSON.
